UNITED STATES PATENT OFFICE.

NELSON M. DELONG, OF WASHINGTON, DISTRICT OF COLUMBIA.

SANDPAPERING-MACHINE.

1,331,843.

Specification of Letters Patent. Patented Feb. 24, 1920.

Application filed June 10, 1916, Serial No. 102,891. Renewed August 16, 1919. Serial No. 318,039.

To all whom it may concern:

Be it known that I, NELSON M. DELONG, a citizen of the United States, and a resident of the city of Washington, in the District of Columbia, have invented a certain new and useful Improvement in Sandpapering-Machines, of which the following is a specification.

My invention relates generally to surfacing machines, and more particularly to sandpapering machines, my primary object being to provide a machine for sandpapering moldings including an arrangement by which the edges between vertical, curved, and horizontal surfaces may be cut sharp and clean and generally better results attained.

A further object is to provide an apparatus whereby the above and certain other advantages may be attained, which will be comparatively simple and inexpensive by which the sand paper and sand paper forms may be readily and quickly changed, by which certain yielding movements of the forms may be permitted, and which will at the same time be strong, durable, and effective in its operation.

My invention, together with its objects and advantages, will be apparent from the following description thereof, reference being made to the accompanying drawings, forming a part of this specification, and wherein—

Figure 1 is a side elevation of the lower part of the machine.

Fig. 2 is a similar view of the upper portion thereof.

Fig. 3 is a sectional top plan view thereof.

Fig. 4 is a transverse vertical section taken therethrough substantially on line 4—4 of Figs. 1 and 2.

Fig. 5 is a detail vertical section taken on line 5—5 of Fig. 3.

Fig. 6 is a transverse vertical section taken substantially on line 6—6 of Fig. 3.

Fig. 7 is a detail vertical section through one of the forms and form boxes, substantially on line 7—7 of Fig. 2.

Fig. 8 is a detail vertical section taken substantially on line 8—8 of Fig. 7.

Fig. 9 is a detail vertical section through another of the forms and its spacing blocks and liners.

Fig. 10 is a detail horizontal section taken substantially on line 10—10 of Fig. 7. 55

Fig. 11 is a detail perspective view of one of the form boxes and its cover, in detached relation.

Fig. 12 is a detail perspective view of one of the forms, spacing blocks, and liners, detached. 60

Fig. 13 is a detail section taken substantially on line 13—13 of Fig. 2.

Referring now to these figures, my invention includes a lower main stationary frame 65 including rigidly connected upright plates 10, 11, and 12, horizontally spaced, and from the central portion of the rear plate 12 of which rise a pair of longitudinally spaced supporting posts 13, these posts being 70 of course rigid with the main frame.

Horizontally along the other portion of the main frame, above and between the plates 10 and 11 as particularly seen in Fig. 4, is the upper run of an endless conveyer belt 75 14, extending over guide rollers 15 journaled in the main frame, and around end rollers 16, the latter of which are journaled in the ends of the main frame, the belt 14 also extending downwardly in the main frame 80 and around a substantially central roller 17 and over rollers 18 and 19, the latter of which are spaced above and at opposite sides of the roller 17, these several rollers 17, 18, and 19 having intermeshing gears 17^a, 18^a, 85 and 19^a by which rotation of one thereof is communicated to the other, for a purpose which will be presently described.

The shaft of the roller 19 is extended forwardly of the machine, and provided with a hand wheel 20 whereby the belt 14 may be moved in either direction by hand, a pair of gear wheels 21 and 22 being provided respectively for engagement with the gears 17^a and 19^a of the rollers 17 and 19. The gears 90 21 and 22 are mounted at opposite ends of a bracket 23, the latter of which is journaled upon a shaft 24 provided with an extending arm 25, the gears so disposed being in mesh with, and at opposite sides of, a gear 26 secured upon shaft 24.

Secured also upon the shaft 24 is a pulley 27 connected by a belt 28 to the pulley 29 of a driven shaft 30, the latter of which is provided with a second pulley 31 connected 105 by a belt 32 to the pulley 33 of a shaft 34.

Mounted on the plate 10 of the main frame is an arcuate bracket 35 having apertures 36 to receive a pin 37 at the free end of the arm 25 before mentioned, in order to hold the said arm and the bracket 23 in the several desired positions. Thus, with the pin 37 in one of the end openings 36 as seen in Fig. 1, the gear 21 is in engagement with the gear 17^a of the roller 17, the belt 14 being thus moved in the direction of the arrow in said figure, while with the pin 37 in the opposite end opening 36, the gear 22 will be in engagement with the gear 19^a of the roller 19, to move belt 14 in the opposite direction. With the pin 37 in the intermediate opening 36, the gears 21 and 22 will be held out of engagement with the gears of the rollers 17 and 19 and thus in neutral position, permitting the belt 14 to be manually moved in either direction by manipulation of the hand wheel 20 before referred to.

The shaft 34 just above referred to, is provided with a second pulley 38 from which extends a belt 39, the latter projecting vertically above the main frame in the space between the plates 11 and 12 of the said frame, and around guide rollers 40 journaled in the inner free ends of an arm 41 journaled at its outer end upon the shaft 34, and thus acting to place tension upon the belt 39 and take up all slack in the latter.

By reference to Fig. 1 it will also be noted that the roller 18 is journaled in a bracket 42 in turn journaled at one end upon the shaft 43 of the roller 17, the opposite end of the bracket 42 being attached to one end of a flexible connection 43 passing around a guide roller 44 and provided at its opposite end with a weight 45 whereby to place desired tension upon the endless conveying belt 14 and prevent undue slack in the latter.

At the upper portions of the vertically projecting supporting posts 13, as best seen by reference to Figs. 4 and 5, is secured a bearing frame 46 having end bearings 47 engaging the said posts and adjustable thereon, and provided with set screws 48 whereby they may be secured in desired adjustment, the said bearing frame extending between the said posts and slightly in advance thereof, as seen by reference to Fig. 4.

An adjusting bracket 49 extending forwardly of, and above, the bearing frame 46, is also provided with upper and lower side bearings 50 adjustably disposed upon the post 13 above and below the bearings 47, and also provided with set screws 51 whereby the bracket 49 may be secured in desired vertical adjustment. An adjusting screw 52 is headed vertically through the central portion of the bracket 49, and has a swiveled connection at 53 upon the bearing frame 46,

the upper end of the screw 52 having a hand wheel 54 providing for its manipulation to adjust the bracket 49 vertically with respect to the bearing frame 46, screw 52 being also provided with a nut 55 thereon above the bracket 49 in order to lock the screw 52 against accidental rotation.

To the forward portion of the bracket 49, as best seen in Figs. 3 and 4, is secured the rear central portion of an upper adjustable frame including a top plate 56 arranged in spaced parallel relation above the upper run of the conveyer belt 14, and having spaced depending strips 57 at intervals along its front and rear edges, it being thus apparent that adjustment of the bracket 49 through the action of the screw 52 also adjusts the upper frame including the horizontal upper plate 56 vertically with respect to the upper run of the conveyer belt 14.

In the lower central portion of the upper adjustable frame is journaled a horizontal crank shaft 58 having cranks 59 and 60 and having a rear pulley 61 above the space between the plates 11 and 12 of the lower main frame, to receive the upper portion of the belt 39 before referred, which thus provides for rotation of the crank shaft, from the cranks 59 and 60 of which extend pitmen 62 and 63 projecting toward opposite ends of the machine, as plainly seen by reference to Fig. 2.

Carried by the upper adjustable frame 56 in its length, are a plurality of set rollers 64, each of which has a shaft 65, the ends of which are received in the inner ends of tubular supports 66, the outer portions of which are adjustably clamped, by means of clamping screws 67, in and through the lower bearing 68 of vertically disposed supporting stems 69, the upper portions of which are cylindrical and pass through bearings 70 at the upper and lower portions of certain of the vertical strips 57 of the upper adjustable frame before referred to, the upper ends of the stems 69 being connected by rigid cross heads 70 above the adjustable frame 56.

By referring to Figs. 2 and 18, it will be noted that each of the stems 69 is provided with a threaded bushing 72 interfitting and bearing upon the lower bearing 70 just above referred to, and which receives thereagainst the lower end of a spring 73 coiled around this particular stem and bearing at its upper end against the upper bearing 70, thus providing for vertical adjustment of the stems 69 and at the same time allowing for uniform tension of the spring 73 at all times.

The rollers 64 are preferably provided with tires 74 of rubber or other suitable yielding material, and are adapted to directly engage the molding, such as shown at A in several of the figures, at a plurality

of points in the length of the molding, upon the upper run of the belt 14, and preferably in grooves of the molding in order to prevent lateral shifting thereof.

5 Below the spaces between the several vertical strips 57 of the upper adjustable frame 56, are disposed form boxes 75, each of which is identical with the others except as regards the particular shape of the forms 10 clamped therein, and includes as best seen in Fig. 11, a rectangular body 76 having an inwardly projecting flange 77 around its lower edge and detachably bolted to a cover 78, the latter of which is provided adjacent 15 its forward and rear edges with upright apertured bearings 79 spaced apart and for a purpose to be presently described. The cover of each of the form boxes is also provided at its opposite side with vertically 20 projecting and apertured lugs 80, the lugs at one side of the boxes nearest the crank shaft 58 being connected to the pitmen 62 and 63, and the adjacent lugs of the other boxes being connected by lugs 81 so that 25 during the operation the several form boxes will be continuously reciprocated.

To this end the forward and rear bearings 79 of each of the form boxes 75 receive the lower side bars 82 of its respective 30 frame, said lower side bars being connected at their opposite ends to uprights 83 journaled through bearings 84 carried by the upright strips 57 of the upper adjustable frame, the upper ends of the uprights 83 being connected by cross bars 85 and the cross bars of each frame being in turn connected at points centrally thereof and above 35 the frame 56, by longitudinal bars 86. Thus each of the form boxes 75 is independently 40 adjustable in a vertical direction, not only of the other form boxes but also with respect to the vertically adjustable frame 56.

Above each of the form boxes 75 the vertically adjustable frame 56 is provided with 45 upstanding lugs 87 upon which are intermediately pivoted rods 88 having flattened central portions 89 provided with longitudinal slots 90 therein through which the upper intermediate bar 86 of the respective 50 form box frame extends, the rod 88 being provided at its opposite end with adjustable weights 91 and 92, as clearly seen by reference to Fig. 6, whereby the pressure upon the particular form box may be regulated.

55 Furthermore, the frame of each of the form boxes 75 may be held in raised position in order that its forms to be herein-after described may be changed, or its sand paper renewed, by means of an arcuate holder 93 pivoted to the vertically adjustable frame 56 at 94 and having inner side shoulders 95 and 96, the former of which is adapted to engage the forward portion of the rod 88 when the latter is elevated to 60 raise the particular form box and its frame

and maintain the latter in upper inoperative position, as shown at the extreme left in Fig. 2.

In the body 76 of each of the form boxes 75, is disposed a frame 97 adapted to rest upon the lower flange 77 of the box and removable from the box when the body 76 thereof is detached from the cover 78, the said frame 97 having surrounding grooves in which are disposed cushion rings 98 and 99, both of 75 which it will be noted project beyond the limits of the frame 97 for engagement with the inner surfaces of the body 76 of the box, in order to allow the frame 97 limited lateral movement, the upper cushion ring 99 also 80 projecting above the top of the frame 97 and with the parts connected as shown in Fig. 7, engaging the lower surface of the cover 78 allowing frame 97 a limited vertical movement. 85

At one side of each of the frames 97 is a vertically journaled post 100 having an upper handle 101 and having a lower cam 102.

The several forms 103 are adjusted within the frame 97 between spacing blocks 104 and 90 one or more liners 105 as seen in Fig. 9, side plates 106 being disposed against the outer faces of the spacing blocks 104 one for engagement against one side of the frame 97 and the other for engagement by the cam 95 102 in order to lock the form and its spacing blocks firmly within the frame.

These form blocks 103 may, of course, be of various shapes dependent upon the particular molding A to be sanded, each of the 100 form blocks 103 having sand paper 107 folded therearound and clamped thereagainst by the spacing block 104 and liners 105 and presented by the form block against the respective surface of the molding A, it 105 being noted that the form block in each instance is extended materially beyond the particular surface to be sanded thereby, so as to project beyond a corner between its particular surface and the surface sanded by 110 the adjacent form block, so that the several form blocks, each of which projects partly into the space to be occupied by another block, thus provide for sharp clean edges between the several angular slots and curved 115 surfaces of the molding A.

It is obvious that the several form blocks 103 may be readily adjusted without removing the same from the frame 97, through the openings of the cap 78, as plainly seen 120 in Figs. 7, 8, and 11, by loosening the cam clamp 102, it being noted that each of the spacing blocks 104 and liners 105 has a shouldered portion 108 at each side, as plainly seen by reference to Fig. 8, resting 125 upon the lower side flanges 109 extending inwardly from the frame 97, so as to prevent lowering movement of the spacing blocks and liners when the form blocks are adjusted vertically and also when the latter 130

are removed for removal of the sand paper 107.

It is obvious that, in view of the extension of each of the form blocks beyond its particular surface to be sanded, as just above described, it is necessary to provide a plurality of form boxes, and that each of the arcuate shaped latches 93, capable of holding a particular form box 75 in upper 10 inoperative position by engagement of its shoulder 95 at one side with the corresponding counterweighted arm 88, is also capable of holding its form box at the proper working level by engagement of its opposite side 15 shoulder 96 with the rod 88. In operation, however, the latch 93 is entirely disengaged from the rod 88 as shown at the right in Fig. 2.

In operation with the controlling arm 25 in neutral position to hold the gears 21 and 22 disengaged, the belt 14 may be rotated through the action of the hand wheel 20, so as to manually shift or feed one end of the molding A to be sanded, beneath the several clutch rollers 64. The frame 56 having been adjusted so that with the several form blocks properly engaged and adjusted within the boxes 75 and the latter, when held by the latch shoulders 96, are in proper working position upon the molding, the operating arm is then shifted to the position shown in Fig. 1, engaging its gear 21 as seen, so that the power supplied to the shaft 30 will be transmitted through the belt 28 and through the gearing connections to the feed belt 14.

At the same time rotation is transmitted to the pulley 61 through the belts 32 and 39, in order to actuate the crank shaft 58 which, through the pitmen 62 and 63 and the links 81, reciprocates all of the form boxes 75 to secure the desired sanding operation upon the molding A.

At any time during the operation where a particularly rough spot on the molding is encountered, the controlling arm 25 may be moved to neutral position and the feed belt 14 shifted backward and forward through the manual actuation of the hand wheel 20, 50 or, it may be shifted to the lower opening 36 of the bracket 35 to carry the moldings in an opposite direction through the reversing of the direction of movement of the feed belt 14.

It is thus apparent that I provide an apparatus readily capable of attaining the objects above set forth, and having the various advantages both as to its construction and operation heretofore enumerated. 60 It is further obvious that the machine is both strong and durable, capable of a wide range of adjustment, and the sanding parts of which are yieldably both laterally and vertically and held, through the action of 65 the counterweighted rod 88 in selected pres-

sure against the molding to be sanded, dependent upon the number of form blocks carried by the particular form box and the relative width of the surfaces of the moldings engaged by such form blocks. 70

I claim:

1. In a molding sander, the combination of a series of sanding devices, an endless feed belt upon which molding is fed beneath said devices, rollers around which said belt 75 extends, certain of which have engaging gears, a driven shaft, a shaft adjacent said roller gears having connection with the driven shaft, a gear on said latter shaft, a controlling arm journaled on said latter 80 shaft, a pair of gears carried by said controlling arm at opposite sides of, and in mesh with, said shaft gear, and shiftable by movement of the said controlling arm into and out of engagement with the gears of 85 the said belt rollers.

2. In a molding sander, the combination of a series of sanding devices, an endless feed belt upon which molding is fed beneath said devices, rollers around which said belt 90 extends, certain of which have engaging gears, a driven shaft, a shaft adjacent said roller gears having connection with the driven shaft, a gear on said latter 95 shaft, a controlling arm journaled on said latter shaft, a pair of gears carried by said controlling arm at opposite sides of, and in mesh with, said shaft gear, and shiftable by movement of the said controlling arm into and out of engagement with the gears 100 of the said belt rollers, and means for securing said controlling arm in adjusted position.

3. In a molding sander, the combination of a series of sanding devices, an endless feed belt upon which molding is fed beneath 105 said devices, rollers around which said belt extends, certain of which have engaging gears, a driven shaft, gearing connections between said driven shaft and said rollers, including rotating gears each of which is engageable with, and disengageable from, one of said roller gears, and means for controlling the said rotating gears. 110

4. In a molding sander, the combination of a series of sanding devices, an endless feed belt upon which molding is fed beneath 115 said devices, rollers around which said belt extends, a driven shaft, gearing connections between said driven shaft and certain of said rollers whereby to move the feed belt, and means attached to one of said rollers for shifting the feed belt by hand. 120

5. In a molding sander, the combination of a series of sanding devices, an endless feed belt upon which molding is fed beneath 125 said devices, rollers around which said belt extends, a driven shaft, gearing connections between said driven shaft and certain of said rollers whereby to move the 130

feed belt, means attached to one of said rollers for shifting the feed belt by hand and including a shaft on which one of said rollers is mounted, and a hand wheel secured upon said shaft.

5 6. In a molding sander, the combination of a series of sanding devices, an endless feed belt upon which molding is fed beneath said devices, rollers around which said belt 10 extends, a driven shaft, gearing connections between said driven shaft and certain of said rollers whereby to move the feed belt, said gearing connections including gears shiftable into and out of engaged position, and 15 means for manually shifting the feed belt.

7. In a molding sander, the combination of a series of sanding devices, an endless feed belt upon which molding is fed beneath said devices, rollers around which said belt 20 extends, a driven shaft, gearing connections between said driven shaft and certain of said rollers whereby to move the feed belt, and means for controlling the direction of movement of the feed belt.

25 8. In a molding sander, the combination of a series of sanding devices, an endless feed belt upon which the molding is fed beneath said devices, rollers around which said feed belt extends, a driven shaft, gearing connections for moving said feed belt in relatively opposite directions extending 30 between the driven shaft and certain of the rollers of the feed belt and including shiftable direction changing gears, and means 35 for controlling the shifting movement of said latter gears.

9. In a molding sander, a plurality of sanding devices, each of which includes a box, a frame within and removable from 40 said box, and a form block adjustably clamped within said frame, said frame having yielding movement with respect to the said box.

10. In a molding sander, a plurality of 45 sanding devices, each of which includes a box, a frame within and removable from said box, and a form block adjustably clamped within said frame, said frame having surrounding grooves, and yielding rings 50 disposed in said grooves and engaging the inner sides of the box.

11. In a molding sander, a plurality of sanding devices, each of which includes a

box having upper bearings, a form block adjustably held within said box, a frame including lower horizontal bars extending through the said bearings and on which the boxes are slidable, and means for reciprocating the several boxes.

55 12. In a molding sander, a vertically adjustable carrying frame, a plurality of sanding frames having bearings on said carrying frame and adjustable vertically with respect thereto, a rod having an intermediate pivotal connection upon the said carrying frame and also having an intermediate pivotal connection with one of the sanding frames, weights adjustably held upon the opposite end portions of the said rod, a sanding box 60 removably mounted in the lower end of each 65 of the sanding frames, and a sanding block 70 adjustably carried by each of the said boxes.

13. In a molding sander, a vertically adjustable carrying frame, a plurality of sanding devices each including a sanding frame 75 vertically adjustable with respect to, and carried by, said carrying frame, counterbalanced pressure means for each of the said sanding frames carried by the carrying frame, and a latch supported by the carrying frame adjacent each of the sanding frames and engageable with the latter to support the same in upper and lower positions.

80 14. In a molding sander, a vertically adjustable carrying frame, a plurality of sanding devices supported by said frame, and a plurality of molding-engaging guide rollers supported by and depending below the said carrying frame, each of said rollers 90 having a shaft projected upon opposite sides thereof, tubular supports into which the ends of said shafts extend, and spring controlled hanger bars having bearing upon the carrying frame and in the lower ends of 95 which said tubular supports are adjustably held.

15. A molding sander, including a main frame, an upper vertically adjustable carrying frame, and a plurality of sanding devices each including a frame independently adjustable vertically on the upper carrying frame, and a sanding box horizontally shiftable in the lower portion of the sanding frame.

NELSON M. DELONG.
